UNITED STATES PATENT OFFICE.

AMOS W. SANGSTER, OF BUFFALO, NEW YORK, ASSIGNOR TO FRANK. H. RANSOM, OF SAME PLACE.

BRACE-HINGE.

SPECIFICATION forming part of Letters Patent No. 295,818, dated March 25, 1884.

Application filed December 10, 1883. (No model.)

To all whom it may concern:

Be it known that I, AMOS W. SANGSTER, a citizen of the United States, residing in Buffalo, in the county of Erie and State of New York, have invented certain new and useful Improvements in Brace-Hinges, of which the following is a specification.

The object of this invention is to produce a strong, durable hinge for trunks or boxes; and it consists of a trunk or box hinge, in combination with a brace adapted to catch and hold the hinge at a certain point when the box-cover is open, all of which will be fully and clearly hereinafter shown by reference to the accompanying drawings, in which—

Figure 1 is a face view of the hinge. Fig. 2 is a section through the hinge and a portion of a trunk and cover, showing it open; and Fig. 3 represents a section through a hinge and brace, also through a portion of a trunk and cover, to which it is attached, showing it closed.

a represents the upper plate of the hinge, and *a'* the lower plate. They are secured together by a joint, *a²*, in the usual way; but the center of the joint *a³* is left open, so that the brace *e*, when closed, may lie flat and close to the hinge and out of the way. The brace is provided at its lower end with an angular or bent portion, *c'*. This portion passes into a narrow opening, *c²*, in the lower hinge-plate. It is formed, as shown, so as to adapt it to turn out as far as is required (see Fig. 2) without being liable to be drawn out of place, and is provided with a narrow portion, *c³*, (shown in Fig. 1,) so as not to reduce the strength of the hinge by making the opening *a³* too wide, and also to assist in strengthening the hinge.

e represents a flat spring secured to the lower hinge-plate by a rivet, *f⁴*. The lower portion of this spring presses against the lower part of *c'*, and thereby forces the brace up flat against

the hinge when or as often as the cover of the trunk or box is closed. (See Figs. 1 and 2.)

The upper hinge-plate, *a*, is provided with an opening, *e'*, and the upper end of the brace is provided with a narrow portion, *e²*, adapted to fit into the opening *e'* when the trunk-cover is open, and thereby acts as a brace to prevent the cover from falling back too far, the corners or shoulders *e³ e⁴* preventing it from going into the opening *e'* too far. The portion *e²* is bent slightly forward, so as to allow it to enter the opening, and, if desired, a projecting piece, *e⁵*, may be placed over the opening *e'* to facilitate the entrance of the part *e²*, and the part *e²* may be made longer, as shown by the dotted lines *g* in Fig. 1, and formed so as to always remain in the opening *e'*, and when the trunk-cover is opened it will pass in until stopped by the shoulders *e³ e⁴*. In that case the spring might be dispensed with. The parts of the cover and trunk *f f'* are hollowed out, so as to leave room for the spring and the portion *e²*.

f² f³ represent a portion of the trunk and cover.

The operation of the device will be readily understood from the foregoing description and drawings.

I claim as my invention—

1. A trunk-hinge consisting of the jointed hinge-plates *a a'*, provided with the openings *c² e'*, in combination with a brace, *e*, having the parts *e²*, the bent portion *c'*, and a spring, *e*, for the purposes described.

2. The hinge *a a'*, having the opening *a³*, in combination with the brace-plate *e*, provided with a narrow portion, *c³*, substantially as and for the purposes specified.

AMOS W. SANGSTER.

Witnesses:

JAMES SANGSTER,
J. M. CALDWELL.
